UNITED STATES PATENT OFFICE

146,167

DESIGN FOR A TRIPOD OR SIMILAR ARTICLE

Louis Bentzman, New York, N. Y., assignor to Acematool Co., Inc., New York, N. Y.

Application May 31, 1946, Serial No. 130,252

Term of patent 14 years

(Cl. D57—1)

To all whom it may concern:

Be it known that I, Louis Bentzman, a citizen of the United States of America, residing at Bronx, New York, in the county of Bronx and State of New York, have invented a new, original, and ornamental Design for a Tripod or Similar Article, of which the following is a specification, reference being had to the accompanying drawing, forming a part thereof.

Fig. 1 is a perspective view of a tripod showing my new design;

Fig. 2 is an enlarged view of the head portion thereof as shown in Fig. 1;

Fig. 3 is an enlarged view of the rear of the head portion thereof as shown in Fig. 1; and

Fig. 4 is an enlarged fragmentary view of one leg thereof in telescoped relation.

I claim:

The ornamental design for a tripod or similar article, as shown.

LOUIS BENTZMAN.
